(57) **CLAIM**

The ornamental design for a perforated cylinder container, substantially as shown and described.

DESCRIPTION

FIG. 1 is a top, front perspective view of a perforated cylinder container;

FIG. 2 is a front elevation view of the perforated cylinder container;

FIG. 3 is a rear elevation view of the perforated cylinder container;

FIG. 4 is a left side elevation of the perforated cylinder container;

FIG. 5 is a right side elevation view of the perforated cylinder container;

FIG. 6 is a top plan view of the perforated cylinder container;

FIG. 7 is a bottom plan view of the perforated cylinder container; and,

FIG. 8 is a top, front perspective view of the perforated cylinder container with a heating device inserted.

The broken lines are for illustrative purposes only and form no part of the claimed design.
